FUEL VAPORIZER

Thomas O. Liles, Detroit, Mich., assignor to Liles
Fuel Vaporizer Corporation, Tyler, Tex., a cor-
poration of Texas

Application February 10, 1936, Serial No. 63,284

3 Claims. (Cl. 257—246)

This invention relates to fuel systems for internal combustion engines and more particularly to the means whereby the temperature of the fuel and air is regulated or controlled in its passage 5 to the carburetor.

A further object of the invention is to provide novel means for heating both the fuel and the air forming the charge by a common means, in which the temperature of the one affects that of 10 the other.

A further object is to provide a practical means for maintaining a quantity of so called low grade or base fuels such as distillate at a temperature near the vaporization point, by utilizing heat from 15 the exhaust of the engine.

It has long been known that distillates and the like possessed fuel values in excess of gasoline, however, the demands for smooth running of the engine and delivery of its power have not heretofore been met in a practical manner when burning 20 low grade fuels, due to the lack of a suitable means for controlling the temperature of the charge. I have provided a practical means for this purpose, and one which is readily and instantly responsive to varying conditions of engine 25 operation and load demand; also a means readily adjustable to accommodate fuels whose vaporization points vary.

Other objects will readily appear and be understood along with the ones hereinabove enumerated by mechanics skilled in the art from the following description together with the accompanying drawing, wherein:—

Figure 1 is an elevation, partly in section of my 35 heater.

Figure 2 is a section along 2—2 of Figure 1.

Figure 3 is an enlarged detail of the upper portion of Figure 1.

In the several figures like references designate 40 similar parts.

10 is the heater having an outer member 11, and inner members 12—12; the latter being preferably joined together at 13, open at their lower ends 14 and having a communicating passageway 45 15 near their upper ends for purposes which will hereinafter more readily appear.

The outer portion 11 and the inner portions 12—12 of heater 10 are joined together adjacent to their lower extremities as by providing a per- 50 forated ring member 16 through which studs 17 pass, after being received by convenient openings in member 11 of the heater to threadedly engage inner members 12. The perforations 18, permit air to enter space 19 between the outer and inner 55 walls of the heater which space may be partially

filled with a suitable medium 20 for filtering foreign substances such as dust, etc., from the air as it travels thru passage 19 into intake 21 of a conventional carburetor (not shown).

The heater may be conveniently mounted upon the exhaust pipe 22 of an internal combustion engine as by providing clips 23 for engaging the exhaust pipe 22 and flanged portions 24 of the heater. An opening 25 is provided in the exhaust 22 which registers with open ends 14—14 of sections 12—12 of the heater. The arrow indicates the direction of normal flow of the hot exhaust gases from the engine. 26 is a butterfly valve, pivotally mounted as at 27 by which registering openings 14—14 and 25 are thermostatically 10 opened and closed as the operation requires. 28 is a thermostat, the outer arm 29 of which is connected to butterfly valve 26 by rod 30. Thermostat 28 is mounted upon pin 31 which latter projects thru and is rotatable in its bearing in inner housing 12, and on its outer end is provided with crank 32 which has a rod 33 pivotally attached thereto and projecting upwardly thru the outer housing of the heater and is threaded at its outer end and there received by adjusting nut 34 by which means the thermostat may be so adjusted as to cause the butterfly valve to open or close the openings 14—14 and 25 at the temperatures desired.

A fuel line 35 leads from a gravity tank located above the carburetor or from a fuel pump not shown and enters one of the elements 12 and is there formed into a coil 35' as it extends downward into the most intense heat area in the element 12 and then leads out as at 36 to the carburetor where the heated fuel is mixed with the heated air from the outlet 21 of the heater and vaporized for admission into the combustion chamber of the engine.

The operation is as follows:

Through adjusting nut 34 the thermostat is set to cause the butterfly valve to open wide into the exhaust manifold to intercept exhaust gases from the engine when it is started, which pass upward about the fuel coil and the thermostat, thence through opening 15 and downward through the other inner element 12 and back into the exhaust pipe 22. As the temperature rises in the heater the fuel in the coil will absorb some of this heat to bring its temperature up to a predetermined point; likewise the air in passage 19 will absorb heat by conduction and convection. As the engine heats up from the working load the thermostat will respond to automatically regulate the amount of exhaust gases 50 55 60 65 70 75 80 85 90 95 100 105 110 115 120 125 130 135 140 145 150 entering the heater, and thereby control the temperature of the fuel and air passing through the heater to the carburetor.

Since different fuels vaporize at different temperatures, it remains only for the operator to adjust the thermostat to provide for the desired temperature for most efficient operation, and obtain the maximum power from any given fuel.

If the fuel used will vaporize at normal atmospheric temperatures the thermostat is adjusted to cause valve 26 to be fully closed whereupon none of the exhaust gases pass through the heater. I prefer to mount my heater in or nearly in an upright position as in this way foreign substances filtered out of the air by the medium 20 will have a tendency to fall by gravity out of the line of passage.

It will be noted that a balanced temperature between the air and the liquid fuel is obtained, which permits of vaporization of the fuel and properly mixing it with the air as the two are brought together in the carburetor.

What I claim is:

1. A charge heater for internal combustion engines comprising an outer member and an inner member with an air passage between said members; the inner member embracing a liquid fuel coil and communicating directly with the exhaust of the engine at one end providing for

the passage therefrom of the exhaust gases, the fuel coil being disposed within the path of travel of said exhaust gases.

2. A charge heater for internal combustion engines comprising an outer member and an inner member with an air passage between said members; the inner member embracing a liquid fuel coil and a thermostat and providing a passage communicating directly with the exhaust of the engine, the fuel coil and thermostat being disposed within the path of travel of said exhaust gases within the said passage.

3. A charge heater for internal combustion engines comprising an outer member embracing an inner member with an air passage between the members; the inner member being formed in two sections each communicating with the exhaust pipe of an internal combustion engine at one of its ends and with the other adjacent its opposite end, heat responsive means disposed within the first of the inner members for controlling the admission of the exhaust of the engine thereto and for controlling its passage from the other of said inner members and a liquid fuel coil disposed within the first of said inner members and within the line of travel of exhaust gases therethrough.

THOMAS O. LILES.
